UNITED STATES PATENT OFFICE.

HARLEY EDGAR FRYE, OF MARIETTA, OHIO.

MOVABLE DAM.

Application filed April 11, 1921. Serial No. 460,198.

To all whom it may concern:

Be it known that I, HARLEY E. FRYE, a citizen of the United States, and a resident of Marietta, in the county of Washington and State of Ohio, have invented certain new and useful Improvements in Movable Dams, of which the following is a specification.

This invention relates to dams of the movable type.

An important object of this invention is to provide a movable dam which may be raised or lowered during any stage of water by means which are entirely under the control of a single operator.

The invention further aims to provide a dam having novel means whereby the entire width of the river may be employed for navigation and which is provided with means for directing the flow of water so as to protect the banks of the river from strong currents of water, and the bed of stream from deep erosion.

A further object of the invention is to provide a movable dam which may be easily exposed for the purpose of repair by workmen who may approach the dam safely in small boats.

A still further aim of the invention is to provide a movable dam having novel means whereby the same is lowered to permit floating ice, etc. to pass and which will automatically return to its elevated position.

The improved dam is further provided with means whereby deposits of mud about the exterior of the dam are prevented and whereby deposits of mud within the shutter of the dam may be carried off.

Other objects and advantages of the invention will be apparent during the course of the following description.

In the accompanying drawings, forming a part of this application and in which like numerals are employed to designate like parts throughout the same,

Figure 1 is a vertical transverse sectional view through the improved dam.

Figure 2 is a fragmentary plan view of the same.

Figure 3 is a vertical transverse sectional view taken on line 3-3 of Figure 1.

Referring to the drawings wherein for the purpose of illustration is shown a preferred

embodiment of the invention, the numeral 10 designates a base or foundation which extends from the bank of the river the entire length of the dam and along the bed of the river. As illustrated in Figure 1, the base 10 terminates below the low water level and is provided with a longitudinally extending main 11 which is adapted to supply water under a high pressure to the several expansion chambers of the dam so that the shutters 12 and the wickets 13 may be raised and lowered at the will of the operator.

The shutter 12 is approximately twenty-five feet in length and has its rear end portion hinged to the base by means of brackets 14 which are anchored to the base by anchor rods 16. It will thus be seen that the longitudinally curved shutter 12 is free to move upwardly and downwardly from the base and when in operative or elevated position supports the wicket 13 in a substantially upright position, so as to form an upper pool. Each wicket 13 is curved longitudinally and has its lower portion reduced so that it may swing between the triangular sides 17 of the shutter. Suitable ears 18 are formed on the wicket and are pivoted to the forward end of the top of the shutter so as to permit the wicket to swing to its operative position illustrated in full lines in Figure 1 or to its inoperative position illustrated in dotted lines in Figure 1.

The shutter cooperates with the lower portion of the wicket and with the adjacent portion of the base in forming an expansion chamber adapted to receive a quantity of water under pressure from the pressure main 11.

Assuming that the wicket 13 is in its inoperative position as illustrated in dotted lines in Fig. 1 a quantity of water under pressure may be introduced into the aforesaid expansion chamber so that the pressure of the water will elevate the shutter and thereby swing the wicket to its upright position as illustrated in full lines. The introduction of the water into the expansion chamber will cause the wicket to rise above the seat 20 immediately behind a transversely extending ledge 21 and in that case chains 22 connected to the intermediate portion of the shutter and to the lower portion of the wicket 13 will serve as a means for limiting the for-

ward swinging movement of the lower portion of the shutter. When the shutter 13 rises above its seat due to the introduction of too much water a small quantity of the 5 water may be discharged by means to be later described so as to permit the wicket to settle to the position illustrated in full lines in Figure 1.

The water supply and discharge means for 10 the expansible chamber includes a water conveyor or conduit generally designated by the numeral 25 which has one end opening directly into the chamber as indicated at 26 and the other end discharging into the lower 15 pool as indicated at 27. The water conveyor which is generally designated by the numeral 25 has a branch 28 which has communication with the pressure main 11 and with a second branch 29 which also has communication 20 with the pressure main. The branches 28 and 29 of the conduit which extends transversely of the base merge into a single 25 passage and have connection with the main as indicated at 30.

25 The discharge of water under pressure from the main 11 is controlled by means of a valve 32 in the branch 28 and by means of a valve 34 in the branch 29.

The operating means for the valves which 30 are in the nature of wheels are arranged within the branches of a tunnel 35. The operator of the dam works within the tunnel 35 and therefore has access to the operating means for the several valves. The tunnel of 35 course extends for the entire length of the dam and may be lighted and may be in communication with the shore by means of a telephone or the like.

The conduit 25 is provided intermediate 40 its ends and between the branches 28 and 29 with an outlet valve 36 which is adapted to be opened when it is desired to discharge the water from beneath the shutter and into the lower pool. When it is desired to introduce 45 a quantity of water into the expansible chamber, the valve 34 is closed and the main inlet valve 32 is opened so that the water may flow from the main 11 through the branch 28 and out through the outlet end 26 into the expansible chamber. Of course, the 50 valve 36 is closed when supplying water to the expansible chamber. When the water under pressure is introduced into the expansible chamber, the shutter is gradually elevated and the wicket 13 is rotated in a clockwise direction until it assumes the position 55 illustrated in Figure 1.

Continued flow of the water into the 60 expansible chamber formed by the shutter and the wicket causes the wicket to move above its seat 20 and thereby expose a plurality of orifices or openings 38 in the upstanding side wall of the ledge 21. With the openings 38 thus exposed, a quantity of water passes 65 through the same and out through a branch

39 which has communication with the conveyor 25 in advance of the valve 36. The water which passes out through the branch 39 enters the branch 29 of the conduit and the pressure of the water in the conduit 29 registers on a gauge 40 which may be viewed by the operator within the tunnel. The pressure of the water in the expansible chamber is indicated by a pressure gauge 41 which may be viewed from within the tunnel. 70 Therefore, when the wicket 13 is extended above the openings 38, the water from the expansible chamber will enter the branch 39 and will thereby cause the gauge 40 to indicate the same pressure as the pressure indicated on the gauge 41. He immediately closes the valve 32 whereupon the wicket may settle on its seat 20 and thereby close the openings 38. It will thus be seen that the wicket in addition to acting as a water draining means functions as a valve in the openings 38. It might be stated that when raising the wicket by water pressure the discharge valve 44 in the outlet end 27 of the conduit or conveyor is closed so that the water discharged through the branch conduit 39 will not be permitted to pass into the lower pool. 80

The branch water conveyor 39 which is connected to the main conveyor 25 between 95 the valves 36 and 44 is provided with a valve 45 which is opened when it is desired to permit the water to flow from the expansible chamber. This of course occurs when it is desired to permit the wicket 13 to settle to 100 its seat 20. The valve 44 is also opened when it is desired to permit a quantity of water to flow from the expansible chamber to permit the wicket 13 to settle.

Should it be desired to lower the wicket 105 the valve 32 is closed so as to cut off the supply of water from the main 11 and the valves 36 and 44 are opened so that the water can flow through the conduit 25 out through the discharge end 27 and into the 110 lower pool. As the water leaves the expansible chamber, the head of the upper pool swings the upper portion of the wicket in an anti-clockwise direction and thereby permits the wicket and the shutter to settle 115 to its lowest position as illustrated in dotted lines in Figure 1.

If for any reason the wicket and the shutter should remain elevated when the valves 36 and 44 are opened, the valve 34 may be 120 opened so as to create a siphon in the discharge end 27 whereby the water will be drawn from the expansion chamber and into the lower pool. As the water is withdrawn from the expansion chamber, the pressure 125 of water in the lower pool will press inwardly on the lower portion of the wicket and cause the same to assume the position illustrated in dotted lines in Figure 1.

If for any reason the wicket 13 should 130

remain elevated, the valves 32, 36 and 44 should be closed and the valves 34 and 45 should be opened so as to permit the water from the main to flow into the branch conduit 39 and through the discharge orifices

38. The pressure of the water flowing through the branch conduit 39 into the expansion chamber will positively unseat the lower portion of the wicket and cause the 10 wicket to swing in an anti-clockwise direction.

The wicket may be caused to fall at any stage of the upper pool above normal for which it is set. This is governed by the 15 weight of the water on the upper portion of the wicket and the opening of valve 32 so as to permit the necessary water to enter the expansible chamber whereby the weight of the water in the upper pool is overcome.

20 It will be observed that when there is no pressure beneath the shutter, the lower end of the wicket will be unseated by the pressure of the water in the lower pool whereby the wicket will be lowered.

25 Pressure of the water beneath the shutter can of course be regulated so that the wicket will lower at any stage desired.

The upstanding side walls 17 of the shutter move within triangular recesses 50 which 30 extend transversely of the base and gradually taper toward one end. A quantity of mud and the like naturally settles in the recesses and to discharge this mud from the recesses I have provided spray pipes 51 which are provided with a plurality of spaced water discharge nozzles 52 for directing water under pressure along the lower portions of the recesses so as to carry the mud from the same. The water and 40 mud is discharged from the recesses through discharge pipes 53 which open into the branch 29 and which are controlled by manually operable valves 54. Valve 55 is connected to the water supply pipe 51 and is 45 within control of the operator. When the several recesses 50 are being sprayed, the water and mud which is conveyed through the discharge pipes 53 enters the branch 29 and passes out through the outlet end 27 50 into the lower pool. During this operation, the valve 44 is of course opened.

When the wicket 13 is lowered, the upper and lower pools will have the same elevation so that the shutter and consequently the 55 wicket may be moved to an upright position. That is to say the wicket 13 and the shutter may be raised out of the water so as to be almost entirely exposed.

When the shutter and the wicket are lowered, the curved formation of the shutter and wicket will prevent the deposit of mud and the like. Furthermore, the velocity of the water is increased by reason of the curved formation of the shutter.

60 Should floating ice or the like strike the

upper portion of the wicket when elevated, the same will be unseated and permits the ice to flow to the lower pool. Pressure of the water causes the wicket to assume its operative position.

Should mud collect in front of the openings 38 when the wicket is down, water under pressure may be discharged by way of the branch conduit 39 through the openings 38 whereby the mud will be carried off 70 to the lower pool over the ledge 21. When water is passing through the expansible chamber from the conduit 39, the forward portion of the wicket is slightly elevated.

When it is desired to clean the chamber 80 beneath the shutter 12 water may be supplied to the chamber from the outer end in such a quantity that the wicket will be elevated so as to expose the several openings. With the openings 38 thus exposed the water 85 within the chamber will pass through the branch conduit 39 and out through the end 27 into the lower pool. However, when performing the cleaning operation, the valves 34 and 36 are closed and the valves 32, 45 90 and 44 are opened.

In the operation and care of the improved dam, the wicket may be raised and lowered during the flood stage or low stage entirely by one man and a lower stage than normal 95 pool need never occur.

A dam constructed in accordance with this invention will not require the use of maneuver boats and large crews of men to operate them, since the operator is located within the tunnel and the branches of the same.

The raising and lowering of this dam can be accomplished at any stage.

With reference to the foregoing description, it will be apparent that a dam constructed in accordance with this invention permits the entire width of the river to be used as a channel and does not necessitate the employment of piers to obstruct navigation.

Having thus described the invention what is claimed is:

1. A dam comprising a base, a shutter mounted thereon, a wicket pivoted intermediate its ends to said shutter and means to supply water under pressure to said wicket and shutter.

2. A dam comprising a base, a shutter swingingly mounted thereon and having sides, a wicket connected to the shutter between said sides and cooperating with the same and the base in forming an expansible chamber, and means to supply water under pressure to said chamber.

3. A dam comprising a base, a shutter mounted thereon and having sides, a wicket swingingly connected to the shutter between said sides and cooperating with the same and the base in forming an expansible chamber, means to supply water under pressure to said 130

- chamber, and a flexible element connecting the intermediate portion of said shutter to said wicket.
4. A dam comprising a base, a shutter hingedly mounted thereon and having sides, a wicket connected to the shutter between said sides and cooperating with the same and the base in forming an expansible chamber, and means to supply water under pressure to said chamber, said base being provided with a seat for the lower portion of said wicket.
5. A dam comprising a base, a shutter hingedly mounted thereon, a wicket hinged to said shutter, and a ledge formed on said base and engaged by said wicket, said ledge being provided with means for directing liquid under pressure into engagement with said wicket to unseat the same.
10. A dam comprising a base, a shutter hinged thereon, a wicket hinged to said shutter, a ledge formed on said base and engaged by said wicket, said ledge and base forming a seat for the lower end of said wicket, and means to supply water under pressure to said wicket and shutter.
15. A dam comprising a base, a shutter hinged thereon, a wicket hinged to said shutter, a ledge formed on said base and engaged by said wicket, and means to supply water under pressure to the lower portion of said wicket for unseating the same.
20. A dam comprising a base, a shutter hinged thereon, a wicket hinged to said shutter, a ledge formed on said base and engaged by said wicket, means to supply water under pressure to the lower portion of said wicket for unseating the same, and a flexible element connecting said shutter to said wicket.
25. A dam comprising a base, a shutter hinged on the base and having parallel side walls, wickets pivoted between said side walls and extending above the shutter, said base being provided with an upstanding ledge constituting a seat and a stop element for the lower portion of said wicket, and means to supply water under pressure to the space beneath said shutter.
30. A dam comprising a base, a shutter hinged on the base and having parallel side walls, a wicket pivoted between said side walls and extending above the shutter, said base being provided with an upstanding ledge constituting a seat and a stop element for the lower portion of said wicket, means to supply water under pressure to the space beneath the shutter, and means to supply water under pressure to the front side of said wicket for unseating the same.
35. A dam comprising a base, a shutter hinged on the base and having sides and a pivoted wicket between said sides, said wicket cooperating with said shutter and the adjacent portion of the base in forming an expansible chamber, and means to supply water under pressure to said chamber for elevating the shutter and wicket.
40. A dam comprising a base, a shutter hinged on the base and having sides and a wicket, said wicket cooperating with said shutter and the adjacent portion of the base in defining an expansible chamber, and means to supply water under pressure to said chamber to elevate the shutter and the wicket, said base being provided with a ledge engaged by said wicket.
45. A dam comprising a base, a shutter hinged on the base and having sides and a pivoted wicket, said wicket cooperating with said shutter and the adjacent portion of the base in defining an expansible chamber, means to supply water under pressure to said chamber to elevate the shutter and the wicket, said base being provided with side walls engaged by said wicket.
50. A dam comprising a base, a shutter hinged on the base and having sides and a pivoted wicket, said wicket cooperating with said shutter and the adjacent portion of the base in defining an expansible chamber, means to supply water under pressure to said chamber to elevate the shutter and the wicket, said base being provided with side walls engaged by said wicket.
55. A dam comprising a base, a shutter hinged on the base and having sides and a pivoted wicket, said wicket cooperating with said shutter and the adjacent portion of the base in defining an expansible chamber, means to supply water under pressure to said chamber to elevate the shutter and the wicket, said base being provided with side walls engaged by said wicket.
60. A dam comprising a base, a shutter hinged on the base and having sides and a pivoted wicket, said wicket cooperating with said shutter and the adjacent portion of the base in defining an expansible chamber, means to supply water under pressure to said chamber to elevate the shutter and the wicket, said base being provided with side walls engaged by said wicket.
65. A dam comprising a base being provided with a ledge engaged by said wicket, and provided with water discharge means.
70. A dam comprising a shutter having side walls, a wicket pivoted to the shutter between said side walls, means limiting the pivotal movement of said wicket, said wicket and said shutter defining an expansible chamber, and means to supply water under pressure to said expansible chamber.
75. A dam comprising a shutter having side walls, a wicket pivoted to the shutter between said side walls, means limiting the pivotal movement of said wicket, said wicket and said shutter defining an expansible chamber, means to supply water under pressure to said expansible chamber, and stationary means to limit the forward movement of said wicket.
80. A dam comprising a hinged shutter having side walls, a wicket pivoted to the shutter between said side walls, said wicket and said shutter defining an expansible chamber, means to supply water under pressure to said expansible chamber, and means to limit the forward movement of said wicket, said means being provided with a water passage.
85. A dam comprising a base, a shutter hinged on the base and having parallel side walls, wickets pivoted between said side walls and extending above the shutter, said base being provided with an upstanding ledge constituting a seat and a stop element for the lower portion of said wicket, and means to supply water under pressure to the space beneath said shutter.
90. A dam comprising a base, a shutter hinged on the base and having parallel side walls, a wicket pivoted between said side walls and extending above the shutter, said base being provided with an upstanding ledge constituting a seat and a stop element for the lower portion of said wicket, means to supply water under pressure to the space beneath the shutter, and means to supply water under pressure to the front side of said wicket for unseating the same.
95. A dam comprising a base, a conduit imbedded in the base and having a branch, a water main connected to said branch, a shutter hingedly mounted on the base, said shutter being formed with side walls and cooperating with the base in forming an expansible chamber, said conduit having communication with said chamber, and a valve interposed in said branch and adapted for controlling communication between said main and said expansible chamber.
100. A dam comprising a base, a conduit imbedded in the base and having a branch, a water main connected to said branch, a shutter movably mounted on the base, said shutter being provided with side walls and
105. A dam comprising a base, a conduit imbedded in the base and having a branch, a water main connected to said branch, a shutter hingedly mounted on the base, said shutter being formed with side walls and cooperating with the base in forming an expansible chamber, said conduit having communication with said chamber, and a valve interposed in said branch and adapted for controlling communication between said main and said expansible chamber.
110. A dam comprising a base, a conduit imbedded in the base and having a branch, a water main connected to said branch, a shutter movably mounted on the base, said shutter being provided with side walls and
115. A dam comprising a base, a conduit imbedded in the base and having a branch, a water main connected to said branch, a shutter hingedly mounted on the base, said shutter being formed with side walls and cooperating with the base in forming an expansible chamber, said conduit having communication with said chamber, and a valve interposed in said branch and adapted for controlling communication between said main and said expansible chamber.
120. A dam comprising a base, a conduit imbedded in the base and having a branch, a water main connected to said branch, a shutter movably mounted on the base, said shutter being provided with side walls and
125. A dam comprising a base, a conduit imbedded in the base and having a branch, a water main connected to said branch, a shutter movably mounted on the base, said shutter being provided with side walls and

cooperating with the base in forming an expansible chamber, said conduit having communication with said chamber, and a valve interposed in said branch and adapted 5 for controlling communication between said main and said expansible chamber, and a branch conduit connected to said main conduit and opening into said expansible chamber.

10 19. A dam comprising a base, a conduit imbedded in the base and having a branch, a water main connected to said branch, a shutter pivotally mounted on the base, said shutter being provided with side walls and 15 cooperating with the base in forming an expansible chamber, said conduit having communication with said chamber, and a valve interposed in said branch and adapted for controlling communication between said 20 main and said expansible chamber, a branch conduit connected to said main conduit and opening into said expansible chamber, and a valve for said branch conduit.

20 20. A dam comprising a base, a shutter 25 hingedly mounted thereon said shutter being provided with side walls and cooperating with the base in forming a chamber, a conduit having one end opening into said chamber and another end discharging into the lower pool, and a branch conduit connected to said first named conduit and discharging water into said chamber, the discharge end of said conduit being provided 30 with a valve.

35 21. A dam comprising a base, a shutter hinged thereon, a wicket pivoted to said shutter, a conduit imbedded in the base and having one end discharging beneath said

shutter and the other end discharging into the lower pool, said conduit being provided 40 with a pair of branches, a valve interposed in the conduits between the branches of the same, and a separate valve for each of the branches.

22. A dam comprising a base, a shutter 45 hinged thereon and having sides, a wicket pivoted to one end of said shutter and cooperating with the same and the base in forming an expansible chamber, a conduit inserted in the base and having one end 50 discharging into the expansible chamber for elevating said shutter and the other end discharging into the lower pool, said conduit being provided with a pair of branches, a valve interposed in the conduits between 55 the branches of the same, a separate valve for each of the branches, and a valve arranged at the outlet end portion of said conduit.

23. A dam comprising a base, a shutter 60 hinged thereon and having sides, a wicket pivoted to said shutter between said sides and cooperating with the same and the base in forming an expansible chamber, a conduit inserted in the base and having one 65 end discharging into the expansible chamber and the other end discharging into the lower pool, said conduit being provided with a pair of branches, a valve interposed in the conduits between the branches of the same, 70 a separate valve for each of the branches, and a branch conduit connected to said first named conduit and discharging into said expansible chamber.

HARLEY EDGAR FRYE.
